Primary Examiner—B. J. Bullock[57] **CLAIM**

The ornamental design for a handle for a cabinet or similar article, as shown and described.

DESCRIPTION

FIG. 1 is a right side view of a handle for a cabinet or similar article showing my new design, the left side being a mirror image;

FIG. 2 is an end view thereof with the opposite end appearing substantially the same;

FIG. 3 is a top view thereof; and

FIG. 4 is a bottom view thereof.
